UNITED STATES PATENT OFFICE.

WILLIAM SPALCKHAVER, OF BROOKLYN, ASSIGNOR TO R. HOE & CO., OF NEW YORK, N. Y.

PAPER-FOLDING MACHINE.

SPECIFICATION forming part of Letters Patent No. 224,051, dated February 3, 1880.

Application filed June 24, 1879.

To all whom it may concern:

Be it known that I, WILLIAM SPALCKHAVER, of the city of Brooklyn, county of Kings, State of New York, have invented an Improvement 5 in Paper-Folding Machines, of which the following is a specification.

This invention relates to that class of folding-machines which are designed for attachment to web-perfected printing-machines as 10 the delivery apparatus thereof.

Of this class of machines the most practical are such whose mechanisms are rotary in their movements, for the reason that as their rotative mechanisms correspond in capacity 15 with those of the printing-machine to which they are attached, it follows that the folding-machine may be thus made to operate with a speed equal to that of the printing-machine, and thus be capable of delivering its product.

These rotating folding-machines have heretofore generally consisted in part of a revolving carrier supporting a folding or creasing blade, (sometimes fixed and sometimes movable either by a reciprocation or a rotation,) 20 which acts to double or crease the sheet of paper along the line of its intended fold into the grasp of folding-rollers or other nipping receiving devices, which, seizing said doubled portion, carry the sheet of paper onward until its front and rear portions are doubled by 25 being laid together, or the same is folded once.

Many objections exist to the use of such folding-blades in these rapidly-operating machines. The effect of their operation is to 30 strike the paper with a percussive blow, which is liable to tear or partially tear the sheet along the folding-line. They do not accurately operate to accomplish the fold at the precise line desired, the position of such fold 35 varying according to the speed at which the mechanisms operate. Their use necessitates a structure that is not only expensive, but liable to derangement and to require frequent adjustment.

My invention avoids the use of any folding-blade whatsoever; and it consists, primarily, in a revolving carrier provided with devices which seize the edges of the sheet at opposite 45 points of the line of its intended fold, and carry the said sheet at the point of its seizure to the action of a pressing or laying roller that fin-

ishes the folding operation, and lays the front and rear portions of the sheet together.

Said invention also comprehends combinations of the various mechanisms, and includes 55 a counting mechanism, all of which will be more fully hereinafter set forth.

In said drawings, Figure 1 represents a right-side elevation of my improved folding-machine. Fig. 2 represents a rear-end elevation thereof. Fig. 3 represents a longitudinal sectional elevation of the cylinder or carrier, showing particularly the arrangement of the folding grippers or fingers therewith. Fig. 4 represents a left-hand longitudinal sectional 60 elevation, on the line *a b* of Fig. 2, of the machine as provided with the necessary mechanisms for imparting two parallel folds to a single sheet. Fig. 5 represents, by a longitudinal sectional diagram, in elevation, the mode of 65 attaching my folding-machine to or combining it with a web-printing machine. Fig. 6 represents, by a longitudinal sectional diagram, a modified form of its attachment to a web-printing machine. Figs. 7 and 8 represent, by 70 an enlarged elevation and plan view, the structure of the counting apparatus.

The folding-machine, as illustrated in Figs. 1 to 4, will first be explained.

A revolving cylindrical carrier, 10, is mounted 80 so as to turn in suitable bearings in the framework, the same being revolved by means of its shaft 21, which is rotated by any suitable driving-wheel and proper gearing. This carrier 10 is provided with a toothed wheel, 20, 85 fast upon its shaft, which meshes with pinions 22, 23, and 24 on the shafts of the tape rollers or pulleys 25 26 27. This carrier is provided at opposite sides with laterally-operating grippers or fingers 3 5, that are suitably shaped or 90 bent so that their ends will lie flat or snugly upon the surface of said cylinder when in their closed positions, said grippers or fingers being fast upon shafts 8 9, that are hung in brackets fast upon the heads of said carrier, and provided 95 with projecting rock-arms 18 19, which are connected together by a rod, 28, whereby the movement of one gripper may be imparted to the other and the two thus caused to move in concert, said rod 28 being provided with an 100 encircling coiled spring, 40, that is seated at one end upon a stop-plate, 46, and at the other

abutting against an adjustable collar, 47, fast upon the rod, the tendency of which spring is to hold said gripers open. Shaft 9 of one of these gripers is provided with a rock-arm, 29, 5 that extends beyond the cylinder-head, so as to ride upon a stationary cam, 30, fast to the frame-work. Thus constructed the gripers or fingers will be carried around with the cylinder or carrier 10, while the rock-arm 29, riding 10 upon the high part of the cam 30, will close said gripers against the pressure of the spring 40, which spring will open said gripers or fingers as the low portions of this cam are traversed by said rock-arm.

15 The series of tapes are arranged so as to conduct the sheets onto this cylinder, permit their leading ends to pass off from the same to aid its doubling and folding, and then guide the doubled sheet properly onward.

20 The upper series, 41, of primary tapes run from the roller or pulleys 26 in contact with the cylinder for a short distance, then lead vertically under roller or pulleys 31, from which they return over the roller or pulleys 32 to the 25 roller or pulleys 26.

The lower series, 42, of the primary tapes lead from the roller or pulleys 33 directly onto the cylinder 10, pass nearly around the same, and return over pulleys 25 to said pulleys or 30 roller 33. These primary tapes, which constitute the conductors for conveying the sheets in succession directly into this folding-machine, might receive said sheets as fed to them from a feed-table fixed directly over the said tapes 35 42 in like manner as are the feed-tables of cylinder printing-machines, a suitable vibrating gage governing the position of each sheet passing to said tapes and onto the cylinder 10; and the roller 26 might have a slight rising-and-40 falling motion, so timed as to drop, seize, and carry forward the sheets at the proper time, as is also common in cylinder printing-machines.

A third set of tapes, 43, extend from pulleys 45 or roller 36 in contact with the under surface of the cylinder, and return around the roller or pulleys 27. These tapes perform the function of aiding in both the folding and delivery of the sheets.

50 A set of guides or rods, 37, are rigidly fixed so as to protrude between the pulleys 27, or into grooves therein, if a roller is used at this point to carry the tapes 43, said guides or rods extending in an inclined direction from said pulleys 27 down to the bed-plate of the machine, and they are supplemented by conductors 38, that are curved to coincide with the upper and outer surfaces of said pulleys, and extend into grooves 14 in the periphery of the cylinder 10, said conductors, with the tapes 43 and guards 37, forming a delivery-channel for once-folded sheets.

The devices thus far described are capable of imparting a single central transverse fold 65 to the sheets, which operation will now be explained.

A sheet, A, fed to and conveyed into this

apparatus by the tapes 41 42, will be carried between them, and directed upon the surface of the carrier or cylinder 10, and onward thereon to the point where the tapes 41 leave said cylinder, at which point the leading end of said sheet will pass off from the cylinder and droop downward, as in Fig. 4. When the center of said sheet has fairly entered upon 70 said cylinder the gripers or fingers 3 5, which at this time have been held open by the operation of the spring 40, will be closed down upon the sheet by the operation of the cam 30, thus clamping the sheet by its edges upon the 75 cylinder at opposite points of the line of its intended fold, which operation of the gripers may be effected, according to the shape of the cam, at any time of their passage, with the cylinder, from the point where the tapes 41 42 80 enter onto the cylinder to that at which the tapes 41 leave it. When the gripers pass the latter point they will cause the sheet to cease to pass off from the cylinder, while continuing to move with it, the line upon which 85 it is held by the gripers or fingers now becoming the leading portion, which, being carried into the nip of the tapes 43, will draw the forward end, now the drooping portion, over the doubling-roller 36, and cause the same to 90 be lapped against the rear portion of the sheet, said sheet being thus doubled in its center, and the two halves, or front and rear portions, of the same being laid together. As the central fold, now the leading edge, is fairly between the tapes 43 and the under surface of the cylinder, the low part of the cam 30 is 95 reached by the rock-arm 29, and the spring 40 again operates to open the gripers or fingers 3 5, thus releasing the folded sheet, and leaving it wholly in control of the tapes 43 and the cylinder-surface, it being carried onward and pressed or smoothed by the action 100 of the pressing-roller 27; and when the point is reached where the conductors 38 intercept the same said folded sheet will be guided over the pressing-roller 27 and down in front of the guides or rods 37, whence it will, by its momentum, follow the guides 37 and descend upon a delivery-board or any common 105 delivery device, as the traveling endless belts 39, which, running over pulleys or rollers 44 45, will feed successive sheets received upon them outward in the direction of the arrow.

In order to count the delivered folded sheets 110 there is attached to the driving-roller 44 of these endless belts 39 a counting mechanism, that is constructed as follows: The shaft 51 of the belt-driving roller 44 carries fast at one end, outside of the frame-work, a double 115 ratchet-wheel that is provided upon one half of the width of its periphery with a continuous set of ratchet-teeth, 4, and on the other half of said periphery with a single tooth, 2. This ratchet-wheel is actuated to rotate 120 the roller-shaft 51 and move the endless belts 39 by means of pawls 16 17, one of which engages the teeth 4 and the other the tooth 2. The pawl 16 carries a weighted arm, 48, press-

ing it to duty, and is pivoted loosely upon a stud, 15, projecting from a rock-arm, 52, that is mounted upon a stud, 53, attached to a bracket extended from the side frame, which 5 rock-arm is vibrated by means of a stud, 1, carried by the arm 54 of a three-armed lever, that turns freely upon the shaft 51 and is actuated by a connecting-rod, 49, pivoted to the end of the arm 55 and eccentrically to the 10 side of the toothed wheel 20. The third arm, 56, of this three-armed lever carries, pivoted to its side, a pawl, 17, which rides up on the plane periphery 13 of the ratchet-wheel, and once 15 during each revolution thereof engages the tooth 2, which may be held to duty either by gravity or a spring.

As each sheet is deposited upon the belts 39 the connecting-rod 49 vibrates the three-armed lever, which, in turn, moves the pawls 16 17. 20 The former, engaging one of the teeth 4, moves it one tooth, and moving the shaft 51, together with the belt-roller 44 and deposited sheets, a slight distance forward, while the pawl 17 rides idly upon the periphery 13 of said ratchet-wheel. When, however, this ratchet-wheel has been so far rotated by the pawl 16 as to permit the pawl 17 (whose movement is of great extent) to pass behind the tooth 2, said pawl will, when vibrated forward, engage said 25 tooth and rotate the shaft 51 and roller 44 a considerable distance, thus moving the accumulated sheets a distance away from the guides 37. This ratchet-wheel has thirty-two teeth, and the throw of the pawl 17 is equal to the 30 feed of seven of these teeth; consequently, when twenty-five folded sheets have been deposited upon the belts 39, the pawl 17 will rotate the ratchet-wheel and pulley 44 such a distance as to carry such sheets bodily forward, 35 and thus distinctly separate them from the next mass of sheets, which will afterward accumulate one by one. Of course this mechanism may be constructed to count any desired number of sheets.

40 This machine may be so constructed as to impart two or more parallel folds to the same sheet, to illustrate which Fig. 4 shows the necessary construction to make two parallel folds, as follows:

45 The cylinder 10 is provided with a second set of grippers or fingers, one, 7, only of which is shown, which grippers or fingers are constructed, mounted, and operated as are those hereinbefore described, being, however, so placed in said cylinder as to occupy a position with respect to the fingers 3 5 suiting the relation the second fold is to bear to the first. In this instance said fingers 7 are at points about forty degrees distant from the fingers 3 5, so that they will double the once-folded sheet, which in extent is a little less than the circumference of the cylinder 10 in its center.

When two sets of grippers are used the second set will be operated by the cam 80, secured 60 to the frame-work at the end of the cylinder opposite to the cam 30.

In producing the second fold, a fourth set

of tapes, 50, are used, which tapes run from a doubling-roller, 34, a short distance in contact with the cylinder 10, then pass over the pressing-roller 25, and return over a roller, 35, which tapes thus stretched form, with the tapes 42, a delivery-passage for the twice-folded sheets. These tapes are illustrated in Fig. 1, (though useless in producing once-folded sheets,) in 70 order to show their relation and that of their driving-roller 25 to the other mechanisms. In this arrangement, as the sheets are not to be guided through the channel formed by the guides 37 and conductors 38, said conductors 75 38 are removed out of operation, as is shown in Fig. 4.

With the machine thus organized, each sheet delivered to the cylinder 10 will be once folded, as before described, its leading edge being released, as stated, and allowed to pass over and droop from the roller 27; but, as its two plies, or front and rear portions, are lapped or doubled together by the action of the doubling-roller 36, and enter between the tapes 43 and 85 the surface of the cylinder 10, the rock-arm of the grippers 7 will ride upon the high part of the cam 80, and be closed down upon the opposite edges of the once-folded sheet at points corresponding to a line passing through 90 its transverse center, and thus held said sheet will be carried upward toward the doubling-roller 34, between which and the surface of the cylinder it will be so doubled or lapped as to lay the two halves of the same upon each 95 other. When this is accomplished the rock-arm of the grippers 7 passes off from the high part of the cam 80, and the spring opens the grippers to release said leading edge, which is then carried into the conducting-channel, 100 formed by the tapes 50 42, that direct it to the action of the pressing-roller 25, and between the rollers 33 35, whence it may be conducted off to be again folded either parallel or at right angles, or it may fall upon a suitable receiving-table, or be conducted to any piling apparatus.

This folding apparatus in either of its described forms, or further modified to produce a third fold, if desired, may be combined with a web-printing machine, so as to fold the sheets produced thereby.

Two forms of such an arrangement of it are shown in Figs. 5 and 6, and it is to be understood that when so combined the shaft 21 of the cylinder 10 may be provided with a suitable toothed wheel, as 70, by which it may be driven through a train of proper gearing-wheels, as 71 72 73, from a revolving shaft or one of the cutting-cylinders, as 59, of said printing-machine. In such arrangement the main feeding-tapes 41 42 will be extended so as to pass around rollers or pulleys 57 58, just in advance of the cutting-cylinders 59 60 of the printing-machine, or they might pass around said cutting-cylinders, occupying the points where the cutting-blades are broken away. In such case said tapes must be speeded to run somewhat faster than the cutting mech-

anism does, in order to accelerate the movement of the leading end of the web, and thus separate or detach its leading end from said web along the line of its partial severance and constitute it a sheet; and even when the cutting-cylinders entirely sever the web, and thus form the sheets, it will be desirable, though not essential, to accelerate these tapes so as to provide for a slight separation of the sheets. With these tapes thus extended the pulleys or roller 26 may act as a returning-roller for the tapes 42, as in Fig. 5, whereby said tapes are bent so as to aid the proper seizure of the sheets between said tapes and the surface of the cylinder 10, or be omitted entirely, as in Fig. 6.

In the arrangement shown in Fig. 5 the tapes 42 run from the roller 58 over the bending-roller 26, and, passing a short distance in contact with the surface of the cylinder 10, thence return under the roller 31 to the roller 58; and the tapes 41 pass from the rollers 57 over the leading-roller 26, nearly encircle the cylinder 10, thence pass over the roller 25, and return to the roller 57 over the rollers 33 and 32. These tapes thus conduct the sheets to the cylinder 10 and within the range of action of the folding mechanism, and the arrangement of the parts is such that the folding mechanism delivers its product in a direction away from the printing-machine.

In the arrangement shown in Fig. 6 the gearing is such that the cylinder 10 revolves in a direction contrary to that shown in the preceding figures, and the taping is modified as follows:

The tapes 42 run from the roller 58 directly onto and nearly around the cylinder 10, being returned over pressing-roller 25 and under a tape-roller, 63. The tapes 41 run from the tape-roller 57 directly onto the cylinder 10, bearing upon a portion of said cylinder, and return under the roller 31 and over the roller 32. The tapes 50 run from the doubling-roller 34 in contact with the cylinder 10, over the pressing-roller 25, over the roller 35, (that is now arranged in close proximity to the roller 63,) and return over a bending-roller, 64. The tapes 42 50 thus form a delivery-channel leading to the rollers 35 63, from grooves in which extend a set of conductors, 61, and a set of guides or rods, 62, that lead to the endless belts 39.

The sheets may be once folded and delivered over the pressing-roller 27, as before described; or the adjustments for making two folds having been made, as hereinbefore explained, the twice-folded sheets will be guided over the pressing-roller 25, and, passing between the tapes 42 and 50, will thence be directed in the apparatus Fig. 5 to any form of delivery mechanism, as hereinafter explained, or, in the apparatus Fig. 6, be directed by the conductors 61 from the rollers 35 down before the guides or rods 62 to the tapes 39.

When the sheets are to be once folded by the apparatus Fig. 6, the guides or rods 62 will be removed, in order not to obstruct the

movement forward of the sheets delivered before the guides 37.

The arrangement of the delivery tapes and rollers for the twice-folded sheets may, as is apparent, be independent of the tapes 42, which would then leave the roller 25 as a mere guide-roller for the return of said tapes 42.

Either or both of the deliveries for the sheets 75 may conduct them to any piling mechanism or to folding mechanisms constructed and arranged to impart one or more folds to said sheets in the same direction or at right angles to the preceding folds.

The cam 80 or cam 30 may be grooved, if desired, so as to impart positive movements 80 in both directions to the fingers or grippers, thus avoiding the use of a spring, as 40.

The doubling-rollers 36 or 34, so far as their 85 function of forming an opposing surface operating in conjunction with the grippers or fingers to lay or double the front and rear ends of the sheets together, and thus finish the folding, is concerned, may have substituted for 90 them a rigid bar with rounded face, or a curved fixed plate, or any similar opposing surface, over which the two plies of the sheets are drawn.

It is obvious that the taping of this folding 95 apparatus in any of its forms may be considerably modified. Thus the series of tapes 41 42, leading the sheets or end of the web to the cylinder 10, may be so arranged as to perform the function of carrying said sheet or the web 100 into a position within the range of action of the grippers or fingers carried by said cylinder; hence neither of said tapes need pass around said cylinder. In like manner the tapes 43 may be omitted, whereupon the sheet folded, 105 by being drawn between the doubling-roller 36 and the cylinder, may, when its leading or doubled edge is released, be propelled onward by the action of the pressing-roller 27, or, if such roller is omitted, simply drop bodily onto 110 a proper receiving device. So, too, in double-folding, the tapes 50 may be omitted, whereupon the once-folded-sheet, seized by the grippers 7 on the line of its second fold, will have 115 its head released at the proper moment thereafter, so as to droop downward, when it will be doubled on its second folding-line between the doubling-roller 34 and cylinder, be propelled onward by the pressing-roller 25, and delivered therefrom in a manner similar to 120 that described for once-folded sheets.

Having now fully described my improvements, what I claim as new, and desire to secure by Letters Patent, is—

1. A rotary folding mechanism consisting 125 of a revolving carrier provided with grippers or fingers operating to seize or clamp the edges of a sheet at opposite points of the line of its intended fold and carry the same onward, and of a doubling device, between which and said 130 carrier the sheet is doubled or folded, all substantially as described.

2. The combination, with a revolving carrier provided with laterally-operating sheet-

seizing grippers or fingers, of a sheet-doubling roller, substantially as described.

3. The combination, with a revolving carrier provided with laterally-operating sheet-seizing grippers or fingers and a sheet-doubling roller, of tapes conveying the sheet to said carrier, substantially as described.

4. The combination, with a revolving carrier provided with laterally-operating sheet-seizing grippers or fingers, of a sheet-doubling roller and a sheet-pressing roller, substantially as described.

5. The combination, with a revolving carrier provided with laterally-operating sheet-seizing grippers or fingers and a sheet-doubling roller, of primary tapes, as 41 42, and supplemental tapes, as 43, substantially as described.

6. The combination, with a revolving carrier provided with two sets of laterally-operating sheet-seizing grippers or fingers, of two sheet-doubling rollers, substantially as described.

7. The combination, with the endless belts 39, of a sheet-counting mechanism consisting of a double ratchet-wheel provided with 25 a continuous set of ratchet-teeth upon one portion of its periphery and a single tooth upon the other portion thereof, with which are combined feeding-pawls 16 and 17, that are simultaneously vibrated by a rod driven by a crank 30 from one of the shafts of the folding-machine, substantially as described.

8. The combination, with the endless belts 39, of the double ratchet-wheel, the pawls 16 17, rock-arm 52, three-armed lever 54 55 56, 35 and actuating crank-rod 49, substantially as described.

In testimony whereof I have signed my name to this specification in the presence of two subscribing witnesses.

WILLIAM SPALCKHAVER.
